UNITED STATES PATENT OFFICE.

CHARLES H. LAY, OF JERSEY CITY, NEW JERSEY, ASSIGNOR TO THE UNION SWITCH & SIGNAL COMPANY, OF SWISSVALE, PENNSYLVANIA, A CORPORATION OF PENNSYLVANIA.

SIGNALING SYSTEM FOR RAILWAYS.

No. 889,469.

Specification of Letters Patent.

Patented June 2, 1908.

Application filed February 27, 1908. Serial No. 418,067.

To all whom it may concern:

Be it known that I, CHARLES H. LAY, a citizen of the United States, residing in Jersey City, Hudson county, New Jersey, have 5 invented certain new and useful Improvements in Signaling Systems for Railways, of which the following is a specification.

My invention relates to signaling systems for railways, and particularly to what is generally known in the art as "overlap systems." In such "overlap systems," as is generally known, the signal for a block section may be held in its danger position by a train, after the train has passed out of the block section 15 for any desired length of track succeeding the block section. For example, the signal for a block section may be held in its danger position by a train while it is passing through any number of succeeding block sections. Such 20 signaling systems may be used to advantage on railways employing short block sections and on which the trains run at considerable speed under short headway.

An object of my invention is to lessen the 25 cost of such installations as well as simplify the arrangement of circuits and also to lessen the number of contacts on the relays generally used in such signaling systems.

I will describe a signaling system embodying my invention and then point out the novel features thereof in a claim.

In the accompanying drawings, Figure 1 is 35 a diagrammatic view of a portion of a railway having a signaling system applied thereto embodying my invention. Figs. 2 and 3 are similar views also embodying my invention. In Fig. 1 the "overlap" is for one block section; in Fig. 2, for two blocks; and in Fig. 3, for five blocks.

40 Similar letters of reference designate corresponding parts in all of the figures.

Referring now to the drawings: 1, 2 and 3 designate block sections of a railway A. The block sections are formed in the usual manner by inserting suitable insulated joints i in 45 one or both of the track rails in a manner well understood in the art. In the drawings I have shown both track rails as being insulated. Each block section 1, 2, 3, etc., is 50 provided with a track circuit which, as is well known in the art, comprises a suitable source of current, C', C², C³, etc., which may be either direct or alternating current, and 55 here diagrammatically illustrated as a battery, the track rails of the block section or

portions of them, and a suitable relay device r', r², r³, etc., which is operable by the current from the source C', C², C³ etc. The relay device r', etc., is here diagrammatically illustrated as an ordinary magnet constructed to 60 attract and release its armature a, according to whether it is energized or deenergized. Of course any other suitable form of relay device may be used. In the present invention when the armature a is attracted by 65 the magnet it is moved against a contact point, commonly called a front contact, to close a circuit.

At the entrance end of each block section a railway signal S', S², S³, etc., is located. Preferably this railway signal will be any of the well known automatic types which comprise a signal device (blade and colored lenses) for giving indications during the day and night, and a motor device for moving the signal device from one position to another. An example of such a railway signal may be found in U. S. Patents Nos. 600,385, granted March 8, 1898, to V. K. Spicer; 611,943, granted October 4, 1898, to J. G. Schreuder; 358,521, 70 granted March 1, 1887, to G. Westinghouse, Jr.; and 745,309, granted November 24, 1903, to J. P. Coleman. In these examples the signal device is in the form of a counterweighted blade which has a normal bias to a 75 horizontal position, which position is termed the "danger" position and is generally an indication to an engineman that the block section at which the signal is located is occupied by a train. The motor device is employed to move the blade to an inclined position, which position is termed the "clear" or "safety" position and is generally an indication to an engineman that the block section 80 is free of trains.

The operation of the motor device to move the counterweighted blade to its "clear" position, takes place when the "signaling circuit" as it is termed, is closed, and in this signaling circuit is included the front contact 95 point and armature of several relays, as the case may be. Obviously, if the "signaling circuit" is open at any point the motor device will not operate to move the counterweighted blade from its "danger" position. 100 As is well known, so long as a pair of wheels and their axle of a train bridges the rails of any block section, they shunt the current from the source C', thus causing the relay r of that block to be deenergized and release its arma- 105 110

ture from its front contact. Also included in this "signaling circuit" is a source of current for either directly operating the motor device of the railway signal, or for operating some electric device which controls the supply of motive power to the motor, according to the type of motor.

In my invention I provide an independent source of current for each railway signal, and carry the circuit for a railway signal through the relays of two or more blocks, according to the length of overlap required. For convenience of illustration the source of current is placed beyond the signal at about the block section where the "overlap" is to end, and, if desired, this arrangement of these sources of current may be followed in practice.

Referring to Fig. 1, B', B², B³, etc. designate the several sources of current (here shown as being batteries) in the "signaling circuits" for the railway signals S', S², S³, etc. The "signaling circuit" for the signal S' may be traced as follows: Starting from one pole of the source B' it is, wires 10, 11, front contact and armature of the relay r² for block section 2, wires 12, 13 and 14, front contact and armature of relay r' of block section 1, wires 15, 16, signal mechanism of the railway signal S', and wire 17 back to the other pole of the source B'. The "signaling circuit" for the railway signal S² may be traced as follows: Starting from one pole of the source B² it is, wires 18, 19, front contact and armature of relay r³ for block section 3, wires 20, 21 and 25, front contact and armature of relay r², for block section 2, wires 12 and 22 to signal mechanism of railway signal S² and wire 23 back to the other pole of the source B². The circuits for the other signals may be similarly traced. It will be seen from this figure that with no train in any block section, all the circuits will be closed and the counterweighted blades of the railway signals S', S², S³, etc. will be in their clear positions. Assume now a train in block section 1. The relay r' of that section will be deenergized by reason of the wheels and axles of the train shunting current from it. Hence, it will release its armature, the signal circuit for the railway signal S' will be broken at that point and the counterweighted blade of the railway signal S' will be moved to its horizontal position. This condition will be maintained so long as the train is in block section 1. When the train enters block section 2 it will shunt current from the relay r of that block section, which relay, becoming deenergized, releases its armature and opens the signaling circuit of railway signal S² at that point, permitting its counterweighted blade to go to its horizontal or danger position. As soon as the train leaves block section 1, the relay thereof will be again energized and will attract its armature to close the signaling circuit of railway signal S' at that point, but the mechan-

ism of this railway signal will not move its counterweighted blade to its inclined position because the signaling circuit is open at the front point in relay r² of the block section 2. Thus the counterweighted blade of railway signal S' will remain in its horizontal or danger position until after the train has completely moved out of block section 2. Thus the "overlap" distance which the counterweighted blades of railway signal S' is held in its horizontal or "danger" position in one block section, and therefore the counterweighted blade will be held in its horizontal or danger position so long as a train or any part of it is in either of two adjacent block sections. The same is true regarding railway signal S², and the counterweighted blade thereof will not be moved to its inclined or "safety" position until the train has completely passed out of block section 3.

Referring now to Fig. 2, the signaling circuit for any one of the railway signals is carried through the front contacts and armatures of the relays for three block sections, that is, through the front contact and armature of the relay of the block section for which the railway signal is provided and through the front contacts and armatures of the relays of the two succeeding block sections, thus making the "overlap" distance in which the counterweighted blade is held in its horizontal or "danger" position two block sections. Take, for example, the signaling circuit of railway signal S'. This circuit starting from the source of current B' may be traced as follows: Wires 24, 25, front contact and armature of relay r³ of block section 3, wires 26, 27, and 28, front contact and armature of relay r² of block section 2, wires 29, 30 and 31, front contact and armature of relay r' of block section 1, wires 32, 33, operating mechanism of the railway signal, and wire 34 to the source B'. It will be seen that when a train is in any of the block sections 1, 2 or 3, the relay thereof will be deenergized to release its armature and thus make a break in the signaling circuit for the railway signal S'. The signaling circuit for railway signal S² may be traced as follows: Starting from the source B², it is, wires 35, 36, front contact and armature of relay r⁴ for block section 4, wires 37, 38 and 25, front contact and armature of relay r³ of block section 3, wires 26, 27 and 28, front contact and armature of relay r² of block section 2, wires 29, 39, operating mechanism of the railway signal S² and wire 40 to the source B². The signaling circuits of the other railway signals may be correspondingly traced.

Referring now to Fig. 3, the signaling circuit for any one railway signal is carried through the front contacts and armatures of the relays of the five succeeding block sections succeeding the block section for which the railway signal is provided as well as the

front contact and armature of the block section for which it is provided. The signaling circuit for the railway signal S' may be traced as follows: Starting from the source 5 B' it is, wires 41, 42 front contact and armature of relay r^6 of block section 6, wires 43, 44 and 45, front contact and armature of relay r^5 of block section 5, wires 46, 47 and 48, front contact and armature of relay r^4 of block section 4, wires 49, 50 and 51, front contact and armature of relay r^3 of block section 3, wires 52, 53, 54, front contact and armature of relay r^2 of block section 2, wires 55, 56 and 57, front contact and armature of relay r^1 of block section 1, wires 58, 59, operating mechanism of railway signal S' , and wire 60 to source B' . Thus it will be seen that a train in either of the block sections 1 to 6 will cause a break to be made in the signaling circuit, and hence the counterweighted blade of the railway signal will be held in its horizontal or "danger" position. The signaling circuit for the railway signal S^2 may be traced as follows: Starting from the source B^2 , it is wires 61, 62, front contact and armature of relay r^7 of block section 7, wires 63, 64 and 42, front contact and armature of relay r^6 of block section 6, wires 43, 44 and 45, front contact and armature of relay r^5 of block section 5, wires 46, 47 and 48, front contact and armature of relay r^4 of block section 4, wires 49, 50 and 51, front contact and armature of relay r^3 of block section 3, wires 52, 53 and 54, front contact and armature of relay r^2 of block section 2, wires

55, 65, operating mechanism of railway signal S^2 and wire 66 to source B^2 . Thus it will be seen that a train in either of block sections 2 to 7 will cause a break in the signaling circuit of railway signal S^2 , thus causing its 40 counterweighted blade to remain in its horizontal or "danger" position.

It will be observed from the foregoing that in each example of my invention that the signaling circuit for each railway signal has an 45 independent source of current and that each signaling circuit is carried through the relays of as many block sections as it is desired to have an overlap.

Of course various modifications may be 50 made by which the principle of my invention may be embodied in the many different signaling systems now well known in the art.

What I claim as my invention is—

In a signaling system, the combination 55 with a series of closed track circuits each comprising a relay having a single front contact and an armature, a railway signal for each block section, and a signaling circuit for each railway signal comprising an independent 60 source of current and the single contact points of two or more relays of the closed track circuits.

In testimony whereof I have signed my name to this specification in the presence of 65 two subscribed witnesses.

CHARLES H. LAY.
